UNITED STATES PATENT OFFICE

GEORGE G. MARSHALL, OF SHAKER HEIGHTS, OHIO, ASSIGNOR TO THE MARSHALL DRUG COMPANY, OF CLEVELAND, OHIO, A CORPORATION OF OHIO

DESIGN FOR A BEVERAGE CONTAINER

Application filed June 6, 1931. Serial No. 40,103. Term of patent 7 years.

To all whom it may concern:

Be it known that I, GEORGE G. MARSHALL, a citizen of the United States, residing at Shaker Heights, in the county of Cuyahoga and State of Ohio, have invented a new, original and ornamental Design for a Beverage Container, of which the following is a specification, reference being had to the accompanying drawing, forming a part thereof.

The single figure of the drawing is an elevation of a beverage container showing an ornamental figure and the remainder of the beverage container being fluted, as indicated in the drawing.

I claim:

The ornamental design for a beverage container substantially as shown and described.

GEORGE G. MARSHALL.
